UNITED STATES PATENT OFFICE.

CHARLES J. MONFORT, OF ST. PAUL, MINNESOTA.

FURNACE.

SPECIFICATION forming part of Letters Patent No. 741,357, dated October 13, 1903.

Application filed December 22, 1902. Serial No. 136,089. (No model.)

To all whom it may concern:

Be it known that I, CHARLES J. MONFORT, a citizen of the United States of America, and a resident of St. Paul, in the county of Ramsey and State of Minnesota, have invented certain new and useful Improvements in Furnaces, of which the following is a specification.

My invention relates to improvements in furnaces; and its object is to provide means for reducing the amount of air entering the furnace over the grate during the operation of firing and to facilitate efficient work by the fireman.

My invention consists, in combination with a boiler-front, of a fire-door on said front and foot-operated lever mechanism for opening and closing said door.

My invention further consists of the elements, features of construction, and combination of parts hereinafter more particularly described and claimed.

In the accompanying drawings, forming part of this specification, Figure 1 is a sectional side elevation of the front of a stationary boiler-furnace, showing my improvement. Fig. 2 is a front elevation of Fig. 1.

In the drawings let A represent the boiler-furnace, B the boiler-front, and C my improvement, which is shown attached to said boiler-front.

My improvement consists, specifically, of the following parts: A door 2, which is pivoted at 3 on the door-frame 4. The door-frame is preferably of the projecting type, as shown in Fig. 1, and is fastened to the boiler-front by means of bolts 4'. The door when closed projects outward from its pivot-point and rests against the front edge of said frame. A lug 5 is cast near the lower edge of the door.

The door swings out when opened into the broken-line position. A shaft 6 is journaled in the bearings 7 above the door, and two wheels 8 and 9, of different diameters, are mounted upon said shaft. A chain 10 is fastened through the perforation 11 in the lug 5 and connects with the larger wheel 8 at 12, so as to wind upon said wheel when the shaft is turned. The bearings 7 are fastened to the boiler-front by means of the bolts 13. A

counterweight 14 is suspended from the wheel 8 by means of the chain 15. The tendency of the weight is to open the door by

revolving the wheel 8. The chain 15 is fastened to the periphery of wheel 8 at 16. A foot-lever D is pivoted at 17 on a frame 18, which is bolted to the floor at 19 in front of the boiler. The end of the lever adjoining the boiler-front is curved up at 20 and perforated at 21. A pulley 22 is journaled below the upturned end 20 of the lever in the frame 23, which is bolted at 24 to the floor. A chain 25 is attached through the perforation 21 in said lever and passes around the pulley 22 and has its opposite end attached to the periphery of the wheel 9 at 25', so as to turn the shaft in the direction of the arrow shown in Fig. 1 when the outer end 26 of the foot-lever is depressed. This movement just described winds the chain 10 on the wheel 8 and opens the door. Turnbuckles 27 are attached to the chains 10 and 25, by means of which the length of the chains may be adjusted.

It is obvious to those skilled in the art to which my invention relates that various modifications of the mechanisms shown and described may be used without departing from the principles which I have applied, the broad idea being the combination of foot-operating lever and counterweight mechanisms with the fire-door of a furnace to open and quickly and automatically close the door, whereby the amount of air entering the furnace over the fire when the door is opened for firing purposes is reduced to a minimum.

Having described my invention, what I claim as new, and desire to protect by Letters Patent, is—

1. A device of the class set forth, consisting of a furnace-front, a door hung upon said front and adapted to swing out, a pair of wheels of different diameters journaled above said door, a connection between said wheels, a second connection between the larger wheel and the swinging end of said door, a counterweight hung from said larger wheel, foot-operating mechanism adjoining said furnace-front, and a third connection between said foot-operating mechanism and the smaller wheel, for the purposes specified.

2. A device of the class set forth, consisting in combination with a furnace-front, of a door hung upon said front and adapted to swing outward, a shaft journaled above said door, a pair of wheels of different diameters

fixed upon said shaft, a connection between the larger wheel and the lower part of said door, a counterweight hung from said larger wheel, a foot-lever adjoining said furnace-front, and a connection between one end of said lever and the smaller wheel; whereby, when the lever is depressed, the shaft is turned and the door opens, and when the lever is released the shaft returns to its original position and the door closes.

3. A device of the class set forth, consisting of a furnace-front, a door hinged to said front and adapted to swing out, a pair of wheels of different diameters journaled above said door, a counterbalance-weight connected

with said wheels, a flexible connection between the swinging end of said door and the wheel of larger diameter, a foot-lever adjoining the furnace-front, and a second flexible connection between said foot-lever and the wheel of smaller diameter, for the purposes specified.

In testimony whereof I have signed my name to this specification in the presence of two subscribing witnesses.

CHARLES J. MONFORT.
